UNITED STATES PATENT OFFICE

LEO SCHROEDER, OF LE MARS, IOWA

HARNESS

Application filed June 22, 1929. Serial No. 372,942.

The present invention relates generally to harnesses and particularly to a device whereby a fast horse and a slow horse may be made to walk evenly together.

5 The device is exceedingly simple in its construction, easy to put in place, inexpensive to manufacture, adjustable, and thoroughly efficient and reliable for the purpose intended.

With the above and numerous other objects in view as will appear as the description proceeds, the invention resides in certain novel features of construction, and in the combination and arrangement of parts as will be hereinafter more fully described and 15 claimed.

In the drawing:

Figure 1 is a top plan view of a pair or team of horses showing my improved structure in place for proper operation,

20 Figure 2 is a perspective view of the device,

Figure 3 is a detail view of one of the snap fasteners, a portion being shown in section,

Figure 4 is a perspective view of one of the 25 angular plates,

Figure 5 is a perspective view of another of the angular plates,

Figure 6 is a detail elevation showing the last mentioned angular plates in use,

20 Figure 7 is a perspective view of a loop member used with the last mentioned angular plate.

Referring to the drawing in detail it will be seen that by way of example I have shown in Figure 1 a slow horse to the left and a fast horse to the right. The numeral 5 denotes an elongated cable of suitable material and intermediate its ends this cable passes through substantially V-shaped plate 6 having longitudinally extending slots 7 in the end portions thereof.

40 A ring or loop 8 of substantially semi-ovate configuration is engaged between the center of the plate and a portion of the cable 5 as clearly illustrated in Figure 6 and an end of a cable 9 passes through the loop 8 and is secured to itself by suitable fastening means 10. The flat side of the ring 8 is engaged in the crotch of the plate 6 and is retained 50 therein by the cable 5.

The cables 5 and 6 are trained through guides 11 on the harness of the fast horse through which the reins usually pass and are secured to the bit of the fast horse by means of snap fasteners 12 and another one of these 55 snap fasteners 12 is secured to the rear end of the cable 5 and engages with the right hand end of the equalizer 13 behind the slow horse.

60 The snap fasteners 12 have swiveled thereto eyes 14 to which the cables are fastened. In order to provide for adjustment, the cable 5, adjacent its rear end, passes through transverse slots 15 in the end portions of a substantially V-shaped plate 16 and then the 65 cable passes through the eye 14 of the rear-most snap fastener 12 and then again passes through the slots 15 and frictionally engages the adjacent portion of the cable.

70 This plate, therefore, functions as a buckle. From a consideration of the exemplification of the device in use it will be seen that the slow horse will hold back the fast horse because when the slow horse gets behind the fast horse this will cause a pull on the cable 5 75 and therefore on both the cables 5 and 9 causing the fast horse to slow down.

76 It is thought that the construction, operation, utility and advantages of this invention will now be quite apparent to those skilled in this art without a more detailed description thereof.

80 The present embodiment of the invention has been disclosed in considerable detail merely for the purposes of exemplification 85 since in actual practice it attains the features of advantage enumerated as desirable in the statement of the invention and the above description.

86 It will be apparent that changes in the details of construction, and in the combination and arrangement of parts may be resorted to without departing from the spirit or scope of the invention as hereinafter claimed or sacrificing any of its advantages.

90 Having thus described my invention, what I claim as new is:

95 A device of the class described for making a fast horse and a slow horse walk evenly comprising an elongated cable, a substanti-

ally V-shaped plate having longitudinal slots in the end portions thereof through which an intermediate portion of the elongated cable passes, a substantially semi-ovate ring on 5 one end of the relatively short cable engaged with the plate and having its flat side disposed in the crotch portion of said plate, snap fasteners on the forward ends of the cables, a snap fastener on the rear end of the elongated cable for adjustably securing said rear 10 end to a base and including an eye through which the cable slidably extends, and means for securing said cable in adjusted position comprising a substantially V-shaped plate 15 mounted on said cable and having transversely extending slots adjacent its opposite ends for the passage of an intermediate portion of the cable and adapted to slidably receive the rear end portion of said cable and maintain 20 the same in frictional engagement with the adjacent intermediate portion thereof, said cable being looped through the eyes on the last mentioned V-shaped plate.

In testimony whereof I affix my signature.
25 LEO SCHROEDER.
